pocket and aligned with the top edge thereof. The front 19 of each fastener 16 is then pushed back so that the pins 18 pierce the pocket material and enter the opening 20 thus gripping the pocket tightly and keeping the upper portion of the pocket taut.

The modification illustrated in Figure 4 is identical to the embodiment illustrated in Figures 1, 2 and 3 except that the bar 15 is provided with a friction coating 21 on the rear side thereof such as rubber or other suitable material which will aid in gripping the articles placed in the pocket when the attachment is in use.

Referring to Figure 6, there is illustrated a modification of my invention which is particularly suitable when the device is to be used in different sized pockets, there being provided means for automatically accomodating the attachment for differences in the width of the pockets. This modification is formed in one piece, preferably a round spring wire or other suitable material. A length of spring wire is shaped into a horizontal portion 22 having a length equal to the width of the narrowest pocket in which it is to be used, two downwardly extending vertical portions 23, 24, two angular sections 25, 26 which together with the vertical sections 23 and 24, respectively, form a V at each end of the device. At the upper end of the outside leg of each V is a bent-over portion designated as 27 and 28, respectively, each terminating in an eye 29 and 30. Each section 27 and 28 is bent outwardly a small amount. Fasteners 16, 16 are fastened to the horizontal section 22 in any suitable manner, as for example by soldering or welding. If desired, the fasteners 16, 16 may be omitted from this modification. This device operates most satisfactorily on pockets which have a width in excess of the horizontal portion 22 but less than the overall length of the device. To install the attachment the two V sections are compressed and the device is placed inside the upper edge of the pocket with the portions 27, 29 and 28, 30 hooked over the outside edge at each end of the pocket. The fasteners 16, 16 are then closed to tightly grip the pocket edge. It will be found that this device will keep the mouth of the pocket stretched taut sufficiently to retain articles placed therein.

The modification illustrated in Figure 7 is identical to that of Figure 6 except that the right hand V has been eliminated and the fastener 16 on the left side has been omitted. This modification has been found satisfactory for use where the width of the pockets used does not differ too great an amount.

Another modification of my invention which will automatically adjust itself to the proper length depending on the width of the pocket where it is to be installed is illustrated in Figures 8, 9 and 10. Two equal rods 31, 32, formed of spring wire or other suitable material are each provided with a fastener 16 mounted on one end thereof, the other ends of the sections or shafts 31 and 32 overlapping to an amount more than half their lengths. The overlap end of the shaft 31 is provided with a ring 34 rigidly mounted thereon and encircling the rod 32. In a like manner the overlap end of the rod 32 is provided with a ring 33 which encircles the rod 31. A

coil spring 35 having one end fastened to the ring 33 and the other end to the ring 34 completes the device. As illustrated in Figure 8 the attachment is in its extended position and can be used in any pocket having a width less than the extended length. To install the device it is necessary only to telescope the device, place it inside the pocket along the top edge thereof, permit the spring 35 to extend the sections 31, 32 until the pocket mouth is taut and then close the fasteners 16, 16. The modification illustrated in Figure 11 is formed from a single length of spring wire or other suitable material and has a horizontal portion 36 from which depends a section 37, 38 at each end thereof. Extending upwardly from each of the dependent legs 37 and 38 is a clip fastener 39 and 40, respectively. The clips 39 and 40 are similar to those widely known and used as paper clips. Each clip 39 and 40 has an inner end 41 and 42 respectively that is bent inwardly as shown in Figure 12. A fastener 43 may be mounted in the center of the horizontal portion 36 if so desired. This modification of my invention is extremely easy to install, it being necessary only to clip each fastener 39 and 40 over the outer edge of each end of the pocket so that the horizontal section lies along the upper inner edge of the pocket to hold the mouth of the pocket taut. The bent in-ends 41 and 42 will grip the pocket and prevent the attachment from shifting its position.

Having thus described my invention, what is claimed is:

1. A garment pocket attachment for keeping the mouth of a pocket taut comprising an elongated slender flexible member, a V-shaped element at each end of said member, each of said V-shaped elements provided with an offset clip whereby said clips may be fitted over the edge of a pocket to hold said elongated member horizontally along the inner edge of the pocket mouth.

2. A garment pocket attachment for keeping the mouth of a pocket taut comprising an elongated slender flexible member, a V-shaped element at each end of said member, each of said V-shaped elements being provided with an offset curved resilient clip whereby said clips may be fitted over the edge of a pocket to hold said elongated member horizontally along the inner edge of the pocket mouth.
